UNITED STATES PATENT OFFICE.

MATTHEW D. S. STILES, OF RIDLEY PARK, PENNSYLVANIA.

SUPPORT.

1,119,896.

Specification of Letters Patent.

Patented Dec. 8, 1914.

Application filed April 6, 1914. Serial No. 629,939.

To all whom it may concern:

Be it known that I, MATTHEW D. S. STILES, a citizen of the United States, residing at Ridley Park, in the county of Delaware and State of Pennsylvania, have invented certain new and useful Improvements in Supports, of which the following is a specification.

My invention relates to improvements in supports, the object of the invention being to provide improved coupling devices connecting the collars and legs, and also adapted to support the lower ends of the legs, permitting steel collars and legs to be employed 15 with their ends cut at right angles.

A further object is to provide a device of this character which is designed for use as a mine support, for a support for tunnels, and in fact for all classes of underground 20 work requiring supports as well as any class of overhead work for which my improvements may be adapted.

A further object is to provide improved coupling devices which may be rolled or 25 otherwise formed of metal and utilized at both ends of the collar and at the lower ends of the legs without change.

Heretofore, in structures of this character, it has been common to use wood and recess 30 the ends of the collar to receive the upper ends of the legs, the latter cut at a bevel to fit into the recessed end of the collar. Where metal collars and legs have been employed, it has been customary to cut the end of the 35 leg at an angle and use brackets or angles to bolt the leg to the collar. With my improved construction, I dispense altogether with the necessity for cutting the ends of the legs at an angle, and provide coupling devices which securely lock the parts together 40 and preclude possibility of movement in any direction.

With these and other objects in view, the invention consists in certain novel features 45 of construction and combinations and arrangements of parts as will be more fully hereinafter described and pointed out in the claims.

In the accompanying drawings: Figure 1 50 is a view in elevation illustrating my improvements. Fig. 2 is a view in elevation at right angles to Fig. 1. Fig. 3 is a fragmentary elevation illustrating a modification. Fig. 4 is a view in longitudinal section of the coupling. Fig. 5 is a fragment-

tary elevation illustrating another modification. Fig. 6 is a perspective view of one of the couplings shown in Figs. 1, 2, and 4.

1 represents a horizontal collar which preferably, although not essentially, consists of an I-beam, and 2, 2, are the metal legs supporting the collar and are preferably H-beams. The ends of the legs 2, 2 are cut at a right angle to the longitudinal axis of the legs, and at their upper ends they are 60 connected to the collar 1 by couplings 3, and at their lower ends they are supported on concrete footings 4 by couplings 3. In other words, all four couplings are precisely alike in construction, the upper couplings being 65 positioned reversely to the lower couplings. In Figs. 4 and 6, I illustrate one of these 70 couplings which consists of a base 5 having three transverse webs 6, 7, and 8, on one face, and a single transverse web 9 on its 75 other face at the same edge as web 6, and located at a right angle to the lower face of base 5. The webs 6, 7, and 8 are located in parallelism and are at an angle to the upper 80 face of base 5. While I have shown a particular number of webs, I would have it understood that the invention is not limited in this particular as I may use any number of webs desired. The web 8 projects in a 85 higher plane than the webs 6 and 7, so that this web 8 is positioned against the end of the collar, while the webs 6, 7, and a transverse enlargement 5^a on base 5 adjacent web 8, support the collar directly thereupon. The 90 couplings 3 at the upper ends of the legs 2, are provided in the web 7 with bolt openings 10 for the reception of bolts 11 which project through the base flanges of the I-beam collar 1, and are secured by nuts 12. The 95 webs 9 of the upper couplings 3 are also provided with bolt openings 13 for the reception of bolts 14 projected through the base flanges of the H-bars constituting the legs 2, and are secured by nuts 15. By reason of this construction and arrangement 100 of coupling, the collar 1 is supported in a horizontal plane, while the legs 2 are at an angle yet the parts are securely coupled without beveling or inclining the ends of the legs, and without cutting recesses in either 105 the collar or the legs.

The couplings 3 supporting the lower ends of the legs receive the lower ends of the legs against the webs 6, 7, and enlargements 5^a, while the webs 8 lie against the 110

inner face of the legs and the webs 9 against the sides of the footing 4, hence said couplings prevent any possibility of lateral movement, and insure a firm and rigid support against strains and stresses from all directions.

The webs 8 are provided with bolt openings 8^a, and these bolt openings 8^a and the bolt openings 13 above referred to in the webs 9, permit the couplings to be secured to the bars and to be anchored in the footing by the bolts 8^b to insure a secure connection of the parts.

In the modification illustrated in Fig. 3, the coupling 16 corresponding to coupling 3, is secured to the collar 1, and leg 2 by angle brackets 17 and 18 with bolts 19 and 20 projected through the collar and leg respectively, and secured by nuts 21 and 25. This coupling 16 is also utilized for supporting the lower end of the leg, and in Fig. 5, another modified form of coupling 23 is illustrated which may be used for connecting an ordinary timber 22 such as commonly used in mines with a metal leg 2 or may be used for metal legs as well. This coupling 23 has webs 24 and 25 at its ends projecting in opposite directions, the former located against the end of the timber 22, and the latter secured by a bolt 26 and nut 27 to the leg 2.

In all forms of coupling, it will be observed that the couplings are so constructed that they provide supporting surfaces at an angle to each other, so that while one surface permits a horizontal positioning of the collar 1, the other surface receives thereagainst the end of a leg at an angle to the collar, hence metal bars may be cut off in lengths and utilized to the best possible advantage in structures of this kind.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A coupling of the character described, comprising a casting having on one side a horizontal surface, and on its other side an inclined surface at an angle to the horizontal surface, said casting having webs at both ends projecting in opposite directions, said webs having openings therein, and said cast-

ing having openings in its intermediate portion, substantially as described. 60

2. The combination with two inclined legs, of couplings located on the upper ends of the legs and having inclined bearing surfaces on the ends of the legs, and horizontal bearing surfaces above the inclined surfaces, a horizontal collar supported upon the horizontal bearing surfaces of the couplings, said couplings having flanges at their outer ends engaging the outer surfaces of the collar, said couplings having flanges at their inner ends engaging the inner faces of the legs, and securing devices securing the couplings to the collar and to the legs, substantially as described. 70 75

3. The combination with a horizontal collar, and inclined legs, of couplings located between the upper ends of the legs and the collar, said couplings having surfaces at an angle to each other, one surface receiving the collar, and the other surface receiving the upper end of the leg, upwardly projecting webs on the outer ends of the couplings located against the ends of the collar, and depending webs on the inner ends of the couplings secured to the legs, substantially as described. 80 85

4. The combination with a horizontal collar, and inclined legs, of couplings located between the upper ends of the legs and the collar, said couplings having surfaces at an angle to each other, one surface receiving the collar, and the other surface receiving the upper ends of the leg, upwardly projecting webs on the outer ends of the couplings located against the ends of the collar, and depending webs on the inner ends of the couplings secured to the legs, substantially as described. 90 95

5. The combination with a horizontal collar, inclined legs below the collar, and footings below the lower ends of the legs, of coupling devices connecting the legs and the collar, and the legs and the footings, all of said couplings constructed alike and having supporting surfaces at opposite sides at an angle to each other, and having a plurality of webs constituting one supporting surface and flanges at its ends, substantially as described. 100 105 110

In testimony whereof I have signed my name to this specification in the presence of two subscribing witnesses.

MATTHEW D. S. STILES.
